UNITED STATES PATENT OFFICE.

ALOIS KOHN AND FRITZ WATZLAWIK, OF VIENNA, AUSTRIA-HUNGARY.

ART OF MANUFACTURING IMITATION TURKEY CARPETS AND CHENILLE WEFT THEREFOR.

SPECIFICATION forming part of Letters Patent No. 353,869, dated December 7, 1886.

Application filed February 24, 1885. Serial No. 156,840. (No specimens.) Patented in France September 22, 1884, No. 164,432; in Belgium September 22, 1884, No. 66,378, and January 21, 1885, No. 67,608; in Germany September 23, 1884, No. 32,466; in England January 22, 1885, No. 909, and in Austria-Hungary February 1, 1885, No. 41,505 and No. 5,338.

To all whom it may concern:

Be it known that we, ALOIS KOHN and FRITZ WATZLAWIK, both subjects of the Emperor of Austria-Hungary, residing at Vienna, in the Province of Nether Austria, in the Empire of Austria-Hungary, have invented certain new and useful Improvements in the Art of Manufacturing Imitation Turkey Carpets and Chenille Weft therefor, (for which Letters Patent have been granted in Austria-Hungary, No. 41,505 and No. 5,338, dated February 1, 1885; in Germany, No. 32,466, dated September 23, 1884; in France, No. 164,432, dated September 22, 1884; in Belgium, No. 66,378, dated September 22, 1884, and No. 67,608, dated January 21, 1885; in England, No. 909, dated January 22, 1885;) and we do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to the art of manufacturing carpets in imitation of what is known as "Turkish" carpets and chenille weft therefor.

It is well known that in the manufacture of Turkey carpets the pile is produced by tying each single pile-thread to the back of the carpet. By these means patterns of any desired number of colors can be produced, which is not the case when carpets, such as velvet carpets, are woven on the Jacquard loom. On the other hand, the tying in of the pile-threads is such a laborious and tedious operation as to materially increase the cost of manufacture of such carpets.

The object of this invention is to avoid the labor connected with the tying in of the pile-threads and produce mechanically carpets similar to those referred to.

The invention has for its further object to provide a mode of operation whereby a certain portion of any desired number of carpets of the same pattern may be produced by one operation.

To these ends the invention consists in the mode of producing the weft or pilestrips, sub-

stantially as hereinafter fully described, and as a step in the manufacture of carpets in imitation of Turkey carpets.

The invention further consists in the mode of producing the imitation Turkey carpets by means of said weft-strips, substantially as hereinafter fully described.

Carpets in imitation of Turkey carpets are according to our method produced mechanically from patterns composed of colored squares that clearly indicate the design and arrangement of the colored squares to be reproduced in the carpet. In these patterns each transverse range of squares corresponds to a shoot of the pile-weft, and each shoot of such pile-weft according to our invention consists of a woven ribbon or strip, the warp of which is composed of wool threads of the required colors. These weft strips or ribbons have weftless edges that are intended to be brushed up for forming the pile of the carpet and a central weftless portion that is intended to represent and imitate the knots in the pile of the genuine Turkey carpet, and that also reproduces the pattern on the back of said carpet.

The manufacture of the carpets in imitation of Turkey carpets according to our invention consists, therefore, of two operations—namely, first, that of weaving the fringed strips or ribbons (which we will hereinafter denominate by the term of "weft" or "pile" strips) of multicolored wool, according to the transverse ranges of the colored squares in the pattern, and, second, the weaving of these weft-strips as a weft into a suitable warp to produce the multicolored pile of the carpet.

In the accompanying drawings, Figure 1 shows a carpet-pattern. Fig. 2 represents a portion of a chain corresponding to the upper transverse range of the pattern combined with the weft, hereinafter described. Fig. 3 shows one strip cut from a chain similar to that shown in Fig. 2. Fig. 4 shows a like strip from which the center weft-threads have been removed for purposes hereinafter described. Fig. 5 represents the back of the carpet woven in accordance with our invention. Fig. 6 is a perspective view of the leaves and reed of a loom, illustrating the manner in which the weft-strips

are placed into the shed of the chain or warp; and Fig. 7 shows on a larger scale the forward end of the shed.

In carrying out the first step of the invention—namely, in producing the weft or pile strips of multicolored wool—we proceed as follows, referring more particularly to Figs. 2, 3, and 4: As many warps or chains of colored-wool threads a are beamed as there are differently figured or colored transverse ranges in the pattern of the carpet, each warp or chain producing any desired number of fringed weft or pile strips of the same transverse range of colors, that are woven into suitable warps for as many different carpets of the same pattern, or into a warp for one carpet as many times as the transverse range of colors corresponding to the strip or ribbon recurs in said carpet. Thus, for instance, the weft strip or ribbon R (shown in Fig. 4) corresponds with the transverse range A' of the pattern shown in Fig. 1, and, supposing that one hundred such weft-strips R are produced from one chain or warp, they may be used as a weft in one hundred carpets for one transverse range of colored squares in the pattern, or in a given number of carpets for a multiplicity of identical transverse ranges of squares in the pattern. The length of these multicolored chains will therefore depend not only on the number of carpets of the same pattern it is desired to produce, but also on the number of times the same transverse range of colors is repeated in said pattern and on the length of the pile of the carpet, as will be readily understood. After a chain is beamed, it is bound at intervals equal to twice the length of the pile to be formed by a few shoots of any suitable weft, the fabric being cut centrally of the weftless portion on opposite sides of the weft to form the fringes for the pile. The width of these multicolored-wool chains, or, in other words, the length of the weft strips or ribbons to be produced therefrom, corresponds, of course, to the width of the carpet to be produced thereby, and the number of colored-wool threads in these chains is usually from one hundred and fifty to two hundred per meter, according to the quality of such carpet.

Having described in a general way the operation of producing the fringed strips or ribbons, we will now proceed to describe the same in detail.

A chain or warp of multicolor wool threads, a , corresponding to the colors in a given transverse range of the pattern, having been beamed in the usual way, we first introduce into the warp a flat wooden bar or slat, b , Fig. 2, the width of which corresponds to the length of pile to be produced. Next we weave into the warp a few shoots, usually four, of wool yarn, c , then one or two shoots of pack-thread, d , and again a few shoots of wool yarn, c' . This constitutes the weft of one strip, after which another flat bar or lath, b' , of the same width as lath or bar b , is inserted, that determines the length of the pile on the opposite side of the

strip or ribbon R, Fig. 2. This operation is repeated as many times as the length of the chain or warp will permit, thus producing a fabric the weft whereof consists of a flat bar or lath, b , wool yarn, pack-thread, wool yarn again, a second flat bar or lath, b' , a flat bar or lath, b , wool yarn, pack-thread, wool yarn again, and a flat bar or lath, b' , and so on throughout the chain or warp.

As hereinabove stated, the described operation takes place for each differently colored or figured transverse range in the pattern, and these fabrics are cut into strips between the laths or bars b and b' , and said strips are numbered according to their order of succession in the pattern, and are finally woven as a weft into any suitable warp, as hereinafter described.

The fabric shown in Fig. 2 will, when cut into strips or ribbons, as described, form the weft for the transverse range A in the pattern shown in Fig. 1, and it will be seen that this transverse range is repeated in that part of the pattern that forms the border of the carpet; hence as many strips cut from this particular fabric are used in one and the same carpet as the transverse range of colors in the pattern corresponding with the warp of this fabric recurs, the other strips being used in other carpets of the same pattern, and so with every fabric the warp whereof corresponds with one of the transverse ranges of squares in the pattern.

The portion of the chenille strip shown in Fig. 4 corresponds with the transverse range of figures A'. (Shown in Fig. 1.)

After the different fabrics have been cut into strips and properly numbered, as described, and to prevent the displacement of the wool-yarn weft-threads c and c' , these are firmly sewed to the warp in a sewing-machine, as shown by dotted lines xx in Fig. 4, and finally the pack-thread wefts d , between said wool-yarn weft-threads c and c' , are drawn out to leave a central weftless portion in the strip or ribbon R, as shown in said Fig. 4, that imitates in the completed carpet the knots of the true Turkey carpet, and reproduces the pattern on the back of said carpet, as shown in Fig. 5. By means of these strips or ribbons the carpets are produced as follows, referring more particularly to Figs. 6 and 7: A pack-thread warp, $a^2 a^2$, is heddled into two leaves, e and e' , of an ordinary loom, the reed f of which contains one thread for each split, and the intervals between said splits are exactly as large as in the reeds used in weaving. The strips or ribbons above described and the chain or warp and the weft are crossed in the same manner as in weaving ordinary linen goods.

In beginning a carpet, a few shoots of wool yarn, g , are first introduced into the chain or warp, and then the first weft strip or ribbon, R—as, for instance, that indicated by A in the pattern, Fig. 1. To prevent the shrinking of the said weft strips or ribbons, they are secured at their ends to a rod or bar, i , triangular in cross-section, which is introduced into the chain or warp in such manner that the

rear or thicker portion will be elevated above the forward or thinner portion of said rod or bar *i*. By means of a brush the fringe at the front edge of the ribbon is brushed up or 5 erected to form the pile. The position of the warp-threads is now reversed, the reed beaten up against the rod or bar *i*, and the latter tilted so as to elevate its front edge above the rear edge, which will enable the operator to 10 brush up the fringe along the said rear edge of the weft strip or ribbon, and when this has been effected the strip or ribbon is detached from the bar or rod *i*, and the latter is withdrawn from the warp or chain.

15 In order to fill out the warp between the pile-threads of adjacent strips or ribbons, a few shoots of strong wool yarn, *j*, Fig. 7, are interposed and a new strip or ribbon introduced as a weft into the warp of pack thread— 20 that A², Fig. 1, for instance—and the operation repeated with such weft strips or ribbons in their proper succession, as at A' A³ A⁴ A⁵, &c., until the carpet is completed, when again a few shoots of strong wool yarn are woven 25 in to bind the edges. The carpet so produced is then finished in the usual manner by steaming, beating, brushing, and shearing.

Having thus described our invention and how the same is to be performed, what we 30 claim, and desire to secure by Letters Patent, is—

1. The improvement in the art of manufacturing chenille weft, which consists in first beaming a chain of multicolored wool corresponding with one of the transverse ranges of colored figures in the pattern, then introducing into said chain a flat wooden bar, then a few shoots of yarn, next one or more shoots of pack-thread, again a few shoots of yarn and 35 a flat wooden bar or lath, repeating the operation by the introduction of another flat wooden bar, and so on until the fabric is completed, then severing the fabric between the wooden bars and removing the pack-threads from be- 40 tween the yarn threads, whereby a chenille 45

strip is obtained that has a central weftless portion, as described, for the purpose specified.

2. The improvement in the art of manufacturing chenille weft, which consists in first beaming a chain of multicolored wool corresponding with one of the transverse ranges of colored figures in the pattern, then introducing into said chain a flat wooden bar, then a few shoots of yarn, next one or more shoots of pack-thread, again a few shoots of yarn and 50 a flat wooden bar or lath, repeating the operation by the introduction of another flat wooden bar, and so on until the fabric is completed, then severing the fabric between the wooden bars, removing the pack-threads from between the 55 yarn threads and sewing the warp to the remaining weft, whereby a chenille strip is obtained that has a central weftless portion, as described, for the purpose specified.

3. The herein-described mode of manufacturing carpets in imitation of Turkey carpets, which consists in first producing as many chenille strips as there are transverse ranges of colored figures in the carpet, each of which chenille strips answers to one of said transverse ranges of colors, removing a portion of the weft of said chenille strips to form a central weftless portion, as described, beaming a chain of pack-thread, weaving said strips in their order into said chain, the fringed edges 70 thereof forming the pile of the carpet as usual, and filling out the chain between the adjacent weft-strips by a few shoots of pack-thread, whereby the pattern of the carpet is reproduced on the back thereof by the weftless portion of the chenille strips and the knots in the Turkey carpet imitated thereby, substantially as and for the purposes specified.

In testimony whereof we affix our signatures in presence of two witnesses.

ALOIS KOHN.
